UNITED STATES PATENT OFFICE.

CHARLES J. REILLY, OF CATSKILL, NEW YORK.

FURNACE FOR WATER-HEATERS.

1,159,090.

Specification of Letters Patent.

Patented Nov. 2, 1915.

Original application filed August 26, 1914, Serial No. 858,603. Divided and this application filed October 30, 1914. Serial No. 869,366.

To all whom it may concern:

Be it known that I, CHARLES J. REILLY, a citizen of the United States, residing at Catskill, in the county of Greene and State of New York, have invented a certain new and useful Improvement in Furnaces for Water-Heaters, of which the following is a specification.

This case is a divisional application of No. 858,603, Charles J. Reilly, water heater, filed Aug. 26, 1914.

My invention relates to furnaces for water heating devices, particularly such as are adapted for the use of various kinds of oil, such as kerosene, as fuel.

One form of my invention is illustrated in the accompanying drawings wherein—

Figure 1 is a diagrammatic side elevation, with parts showing on dotted lines—Fig. 2 is a cross section of the heater,—Fig. 3 is a plan section of the same, as indicated on line 3—3 of Fig. 2,—Fig. 4 is a perspective of the air valve ring—Fig. 5 is a vertical cross section of the generator.

Like parts are indicated by the same letter in all figures.

For purposes of illustration I have shown my invention in connection with an ordinary range or furnace hot water boiler, which may be an ordinary receptacle for holding hot water under pressure. In view of the necessity of such device for use in heating water in the household, and for many commercial purposes in the rural districts, cities, towns and villages, where no artificial or natural gas can be secured for the purpose, and where gasoline if used for the purpose is dangerous to life and property, I have invented an arrangement in which ordinary kerosene or crude oil can be used for the purpose efficiently without fear of any danger, external heat or obnoxious odors. The greatest benefit will be derived in many cases by those who have a water heating apparatus connected to a furnace or coal cook stoves, only used for a few months in each year, thus necessitating resorting to laborious and troublesome means of secur-

ing hot water for the bath or other household or commercial purposes. My invention can be connected up with, and without disturbing any other arrangement for heating water and only used when necessary without disconnection.

A is a hot water receptacle here shown in the form of a cylinder.

B is a cylindrical heater housing containing the heating coil B¹, whence leads the pipe C C respectively to the top and bottom of the receptacle A. The heater B is connected with the source of fuel supply D, the fuel in this case being kerosene, by means of the pipe E, which leads downwardly from the reservoir and passes through the wall of the furnace.

F is a valve to regulate the quantity of oil passing through the pipe E.

G is a generator, the essential part of which is the annular part G¹ with screw threaded hollow projections, G² on its opposite sides and a central plate G³. Into one of these connections G² leads the pipe E and from the other emerges the pipe G⁴ which is shaped as shown and terminates in the cap H, perforated to allow the liquid in the pipe to escape and placed beneath the plate G³. This plate acts as a baffle to distribute the upwardly flowing gas.

The furnace consists of the casing K, with the fire brick lining I.

J J are perforations through the casing and fire brick lining I.

J¹ J¹ are perforations in the valve ring L, which is supported in the annular support M, and whose two ends are adapted to be drawn together by the thumb screw N to lock it in any desired position. The quantity of air is regulated by moving and setting this valve ring.

In the heater housing B is the coil B¹, connected with pipes C at top and bottom as indicated. I use a double conical coil as indicated with the baffle plate P at the middle and narrowest portion to prevent the hot gases from passing up through the center of the coil.

R is a smoke stack leading from the top of the heater B and discharging into the chimney Q.

S is a controlling damper in the stack R.

5 By this means the gases of combustion may be discharged in the open air.

The jacket K extends so as to inclose not only the furnace, but also the heater, and is provided above the fire brick with the asbestos lining T and the inner metal protecting casing K¹.

In the bottom of the furnace I place a loose bed of asbestos U to absorb the oil that is allowed to run out of the perforation

15 in the cap H for use in heating up the generator in starting up the apparatus

20 V is a tube leading from the water circulating pipe C down to just above the baffle plate of the generator, and it is controlled by the valve W. Through it water may be discharged upon the baffle plate.

25 X is an auxiliary reservoir and Y a valve connected with the pipe E, whereby the supply of kerosene may be cut off when the auxiliary reservoir is full, the latter being a charge for a specific piece of work or time.

30 Z is the cold water inlet pipe which leads to the bottom of the receptacle A, and Z¹ the hot water service pipe which leads from the top thereof.

35 Z² is a stand or bracket on which the receptacle is supported, and Z³ is a like stand or bracket on which the furnace is supported.

40 X¹ is a check valve or air release communicating with the reservoir X to permit air to enter at the top to displace the liquid which runs out when the valve Y is shut and the valve F is open. It, however, does not permit the discharge of oil when the system is full.

45 The use and operation of my invention is as follows: The cold water and the hot water pipes are connected to the distributing system of the house in such manner that the receptacle stands full of water, and under normal conditions this water will be cold.

50 If now, the operator desires to heat the water, he will turn the valve ring L so as to expose the interior of the furnace. He will then open the valves Y and F sufficiently to allow oil to enter through the pipes E and G⁴ to the interior of the furnace and into the bed of asbestos U in the bottom of the furnace. He now closes valves Y and F, and by match or taper lights the oil in the asbestos within the furnace, and this oil burning will bring the generator to such a temperature as will cause the formation of gas. The

60 operator now opens the valves Y and F, whereupon the oil which passes through the pipe E into the generator emerges from the cap H as gas, and as such it is immediately burned.

The products of combustion pass upwardly through the top of the furnace, through the heater, and if the damper S is open, out through the stack and chimney into the open air. Such products of combustion however, pass laterally upwardly through the coils B¹, being deflected by the baffle plate P, so that at that point all of the products of combustion will have passed through the lower set of coils and thereafter will pass inwardly through the upper set of coils, thus heating the water which passes through these coils.

If the operator desires to heat a certain specified amount of water or to have the apparatus run for a predetermined period, he will open the valve Y, or otherwise manipulate the valves so that the auxiliary reservoir X fills with oil, and he may then close the valve Y and proceed as above, whereupon the fire will be maintained only so long as the oil in the auxiliary reservoir lasts.

In apparatus of this kind trouble is frequently experienced with respect to the formation of soot and like deposits on the coils. For this reason I provide the pipe V and controlling valve W, so that when the valve W is open a certain amount of water will pass through the heater and be discharged upon the hot baffle plate G³, when it is immediately converted into steam, and this steam serves to clear the exterior surfaces of the coils of the deposits thereon due to the passage of the products of combustion.

I claim:

1. The combination with a combustion chamber of a gas generating coil located in said chamber above the air supply, a heating and deflecting plate integral with the coil, a burner located beneath said plate, a gas supply pipe leading from the generating coil to said burner, an oil supply pipe communicating with the generator, and means for discharging water in a liquid form upon the upper surface of said plate independent of the gas and oil supply.

110 2. The combination with a combustion chamber having an absorbent wick-like bottom, of a gas generating coil located in said chamber above the air supply, a heating and deflecting plate integral with the coil, a burner located beneath said plate, a gas supply pipe leading from the generating coil to said burner, and an oil supply pipe communicating with the generator, and means for discharging water in a liquid form upon the upper surface of said plate independent of the gas and oil supply.

115 3. The combination with a combustion chamber having an adjustable air supply, of a gas generating coil located in said chamber above the air supply, a heating and deflecting plate integral with the coil, a burner located beneath said plate, a gas supply pipe

leading from the generating coil to said burner, and an oil supply pipe communicating with the generator, and means for discharging water in a liquid form upon the 5 upper surface of said plate independent of the gas and oil supply.

In testimony whereof, I affix my signature

in the presence of two witnesses this 24th day of October 1914.

CHARLES J. REILLY.
